UNITED STATES PATENT OFFICE.

ANGUS LAMOND, OF TAKOMA, DISTRICT OF COLUMBIA.

DESIGN FOR A SEWER-BLOCK.

SPECIFICATION forming part of Design No. 20,357, dated December 2, 1890.

Application filed August 21, 1890. Serial No. 362,686. Term of patent 7 years.

To all whom it may concern:

Be it known that I, ANGUS LAMOND, a citizen of the United States, residing at Takoma, in the District of Columbia, have invented and produced certain new and original Designs for Sewer-Blocks; and I do hereby declare the following to be a full, clear, and exact description of the invention, such as will enable others skilled in the art to which it applies to make and use the same.

Figure 1 represents a perspective of a block embodying my design, and Fig. 2 an end view of the same.

A represents a block made of any desired material, and the design thereof lies in the particular configuration set forth, and which is as follows:

A' represents a curved surface terminating at the edges with the flat faces a and a' and at the ends with the flat faces a² and a³. The

flat faces a and a' are formed on radial lines, the point of radiation of which is the same as the center of the circle of which the curved surface A' forms a part. The side of the block back of the curved surface A' (and marked A²) is polygonal, the faces of which are marked a⁴, a⁵, and a⁶ and form obtuse angles with each other and with the flat faces a and a'. These ends a and a' may be provided with holes a⁷, which extend through the blocks.

What I claim as new is—

The design for the block, substantially as shown and described.

In testimony whereof I affix my signature in presence of two witnesses.

ANGUS LAMOND.
